UNITED STATES PATENT OFFICE.

JAMES A. KAMMERDINER, OF LOS ANGELES, CALIFORNIA.

ROTARY JAR.

Application filed December 16, 1924. Serial No. 756,208.

To all whom it may concern:

Be it known that I, JAMES ALLEN KAMMERDINER, a citizen of the United States, and resident of Los Angeles, in the county of Los Angeles, State of California, have invented new and useful Improvements in a Rotary Jar, of which the following is a specification.

This invention relates to a rotary jar for assisting in dislodging tools, equipment, or like devices which have become stuck in holes, such as oil well holes. The present invention pertains broadly to that class of devices disclosed in Reissue Letters Patent No. 15,760, February 12, 1924, wherein an appliance is described for use in hydraulic rotary drilling of wells. In such a device a circulation of water or mud must be maintained in the hole, and, to this end, a jar is provided which may be interposed in the circulation line and form a part thereof.

The present invention contemplates use of a chamber in the jar to house the trip mechanism. The primary object of this invention is to provide a chamber of the character described wherein the sum total of the space therein is at all times the same regardless of moving parts therein, thus, permitting complete closure. In devices of this character, if the chamber is not so constructed, mud, grit, and water may enter, wearing the parts and acting as a check upon the blows delivered on tripping the jar.

An embodiment of the invention is illustrated in the accompanying drawing, in which:

Fig. 1 is an axial section through the jar in contracted condition, part being shown in elevation; Fig. 2 is another axial section showing the jar in expanded position; Fig. 3 is a section on the line 3—3 of Fig. 2; and Fig. 4 is a section as seen on the line 4—4 of Fig. 2.

Referring more particularly to the drawing, 5 indicates a cylindrical body or cage having a threaded tapered pin 6 at the upper end. The bore 7 is threaded at the lower end to receive a plug 8. The upper end of the bore is reduced in diameter to form a plunger chamber 9. Within the bore is a mutilated thread 10 formed of two diametrically opposed portions occupying each approximately one-quarter of the periphery. These threads form in effect shoulders which are inclined to the axis of the tool. The

threads may be closed at one edge by fillets 11.

Disposed within the cage is a hammer comprising an annular hammer head 12 adapted to engage the anvil 13 formed on the plug 8. The hammer head is provided with a tubular shank 14 which slidably extends through an opening in plug 8 and is provided at the lower end with a pin 15 for attachment in the string of pipe. The shank is extended above the head as indicated by 16 and is provided with threads 17 corresponding to the threads on the cage. The shank is extended upwardly to form a tubular plunger 18 slidably mounted in the chamber 9. At the upper end of the plunger are cup leathers 19. It is obvious that a continuous closed passage is formed from the pin 6 through the body to the pin 15. This construction provides for connecting the tool in circulation line.

The jar is placed in a string of tubing or pipe, a fishing tool depending from the bottom of the string. Upon getting a grip upon the lost part or the device to be dislodged, the jar is contracted by lowering the string so that the segments of the thread on the hammer shank slide between the segments of the thread on the cage. The threads on the hammer and cage registering, the cage is rotated so that the threads mesh, a quarter turn being sufficient. The fillets prevent the hammer from riding out of mesh with the cage threads; and furthermore, in this position, continuous rotation of the string may be effected. In the action of the hammer head 12 being moved from contracted to expanded position, the plunger 9 will recede into the plunger chamber, whereas, the shank 14 of equal size will be intruded into the chamber 7. Thus, the total recession of plunger 18 is exactly equal to the intrusion of shank 14 and the summation of the displacement is equal. It is obvious that movement of the hammer head 12 downwardly will cause no difference in the volume total of space within the chamber as the enlargement on one side of the hammer head is compensated for by the reduction on the other side. Having placed the threads in mesh a pull is exerted upon the string, and, after the proper tension has been reached, the jar is turned or rotated. Rotation of the two parts causes segments of the threads to ride out of mesh and trip, whereupon the hammer strikes the

anvil causing a jar or impact. Iron or metal pipe or tubing used in oil well work has elasticity which is very appreciable in a string of the length commonly used in wells. This elasticity assists in creating the jarring effect upon release of the hammer. The cup leathers 19 are so positioned that on the downward stroke of the hammer there is substantially no resistance due to their position in the plunger chamber. Upon the upward movement of the hammer head, the cup leathers expand and prevent any liquid from entering the trip chamber.

15. What I claim is:

1. A rotary jar adapted to be connected in a string of pipe comprising a cage having a trip chamber closed at the lower end and provided with an anvil for impact of a hammer thereon, a tubular reciprocable hammer having a hammer head mounted in said chamber and slidably extending through the lower end of said chamber, a plunger chamber communicating with and at the upper end of said trip chamber, the upper end of said hammer being slidably mounted in said plunger chamber, said plunger chamber being adapted to communicate with said string, trip means on said hammer and said cage to arrest the movement of said hammer intermediate the ends of said trip chamber and to hold said cage and hammer under tension in this position, said trip means being arranged to be released by relative rotation of said cage and hammer and to freely permit said hammer to slide longitudinally in said cage whereby said head may be arrested by impact on said anvil.
2. A rotary jar adapted to be connected in a string of pipe comprising a cage having a trip chamber closed at the lower end and provided with an anvil for the impact of a hammer thereon, a tubular reciprocable hammer having a hammer head mounted in said chamber and slidably extending through the lower end of said cage, a plunger chamber communicating with and at the upper end of said trip chamber, the upper end of said hammer being slidably mounted in said plunger chamber, said plunger chamber being adapted to communicate with said string, trip means on said hammer and said cage to arrest the movement of said hammer intermediate the ends of said trip chamber and to hold said cage and hammer under tension in this position, said trip means being arranged to be released by relative rotation of said cage and hammer and to freely permit said hammer to slide longitudinally in said cage whereby said head may be arrested by impact on said anvil, and cup leathers on the plunger portion of said hammer with the leathers dished away from said trip chamber.

3. A rotary jar adapted to be connected in a string of pipe comprising a cage having a cylindrical trip chamber closed at the lower end and provided with an anvil for impact of a hammer thereon, a cylindrical hollow reciprocable hammer rod having a hammer head mounted in said chamber intermediate its ends and slidably extending through the lower end of said cage, a plunger chamber communicating with and located at the upper end of said trip chamber, the upper end of said hammer rod being slidably mounted in said plunger chamber, said plunger chamber being adapted to communicate with said string, trip means on said hammer and said cage to arrest the movement of said hammer intermediate the ends of said trip hammer and to hold said cage and hammer under tension in this position, said trip means being arranged to be released by relative rotation of said cage and hammer and to freely permit said hammer to slide longitudinally in said cage whereby said head may be arrested by impact on said anvil.

4. A rotary jar adapted to be connected in a string of pipe comprising a cage having a cylindrical trip chamber closed at the lower end and provided with an anvil for impact of a hammer thereon, a cylindrical hollow reciprocable hammer rod having a hammer head mounted in said chamber intermediate its ends and slidably extending through the lower end of said cage, a plunger chamber communicating with and located at the upper end of said trip chamber, the upper end of said hammer rod being slidably mounted in said plunger chamber, said plunger chamber being adapted to communicate with said string, trip means on said hammer and said cage to arrest the movement of said hammer intermediate the ends of said trip chamber and to hold said cage and hammer under tension in this position, said trip means being arranged to be released by relative rotation of said cage and hammer and to freely permit said hammer to slide longitudinally in said cage whereby said head may be arrested by impact on said anvil, and cup leathers on the plunger portion of said hammer with the leathers dished away from said trip chamber.

5. A rotary jar comprising a cage having an anvil at the bottom thereof, a hammer slidably mounted therein for axial movement, said hammer having a cylindrical hollow rod with a head intermediate the ends thereof so that when expanded said head may engage said anvil, trip means to arrest the movement of said hammer above said anvil and to take the tensile strain characterized by said trip means comprising oppositely disposed mutilated thread sections on said cage and corresponding segments on said shank, said cage being pro-

vided at its upper end with a plunger chamber in which the upper end of said hammer rod slidably extends and being of the same diameter as the portion of the hammer rod 5 extending through the bottom of said cage.

6. A rotary jar comprising a cage having an anvil at the bottom thereof and a hammer chamber therein, a hammer slidably mounted therein for axial movement, said 10 hammer comprising a cylindrical hollow hammer rod having a head intermediate its ends so that when expanded said head may engage said anvil trip means to arrest movement of said hammer above said anvil 15 and to take tensile strain characterized by said trip means comprising oppositely dis-

posed mutilated thread sections on said cage and corresponding segments on said shank, said cage having a plunger chamber at its upper end with said trip chamber, the upper end of said hammer rod being slidably mounted in said plunger chamber, said plunger chamber being adapted to communicate with said string, and cup leathers on the plunger portion of said hammer with the 20 leathers dished away from said trip chamber.

In witness that I claim the foregoing I have hereunto subscribed my name this 3rd day of December, 1924.

JAMES A. KAMMERDINER.
